FIG. 1

FIG. 2

INVENTOR

Frederick K. Maerz,

By Hull, Smith, Brock & West

Attn:

UNITED STATES PATENT OFFICE.

FREDERICK K. MAERZ, OF CLEVELAND, OHIO.

DESIGN FOR A RING FOR ELECTRIC-LIGHTING FIXTURES.

48,035.

Specification for Design.

Patented Oct. 26, 1915.

Application filed June 7, 1915. Serial No. 32,742. Term of patent 3½ years.

To all whom it may concern:

Be it known that I, FREDERICK K. MAERZ, a citizen of the United States, residing at Cleveland, in the county of Cuyahoga and State of Ohio, have invented a new, original, and ornamental Design for Rings for Electric-Lighting Fixtures, of which the following is a specification, reference being had to the accompanying drawing, forming part hereof, wherein—

Figure 1 is a side elevation, and Fig. 2 a plan view of half of the ring exhibiting my new design.

I claim:

The ornamental design for a ring for electric lighting fixtures as shown.

FREDERICK K. MAERZ.

Witness:

HUGH B. MCGILL.
